UNITED STATES PATENT OFFICE

SKILES E. TEST, OF INDIANAPOLIS, INDIANA

AMUSEMENT DEVICE FOR SWIMMING POOLS

Application filed October 17, 1930. Serial No. 489,343.

This invention relates to an amusement device for swimming pools.

The chief object of this invention is to provide a device which will permit of obtaining sea-sled amusement upon confined pools.

Heretofore sea-sled amusement has been confined to large bodies of water which will support a power boat to which a sea-sled is attached by a single line cable or the like.

The present invention contemplates the obtaining of sea-sled action for amusement and its application to a confined area which would not ordinarily be of sufficient size to permit the maneuvering of a power boat.

One feature of the invention consists in the portable character of the power unit employed.

The full nature of the invention will be understood from the accompanying drawings and the following description and claims:

In the drawings Fig. 1 is a top plan view of the invention, including a pool, sea-sled and one form of reciprocating mechanism for the latter.

Fig. 2 is an elevational view of the semi-portable power mechanism embodied in the preferred form of the invention.

In the drawings 10 indicates the pool which includes the usual walk or pathway 11 at its edge. 12 indicates a post at one side of the pool and 13 indicates a winding drum which has the steeply curved surface as illustrated.

35 A cable 14 is wrapped about the periphery of the drum and approximately four or more times, and the cable is endless, passing over the sheave 15 of the pulley having the eye 16 by which it is secured to the post 12. A suitable cord or cable 17 secured at one end of the eye 16 is suitably secured to the post 12 in any desired or preferred manner. However, the distance that the pulley is positioned from the post determines the tautness of the 45 endless cable 14. This cable should be maintained reasonably taut at all times. A cable similar to wash line or the like, is suitable but due to climatic changes, this cable will elongate and shorten, wherefore, the adjustability obtained through the pulley anchorage or

mounting 17 is provided. A sea-sled 18 is conventionally illustrated in Fig. 1 and is suitably secured to the endless cable 14 by the line 19. The endless cable 14 is preferably positioned at a height of about three feet or 55 so above the surface of the pool.

The steepness of the curved sides of the drum is such that as the cable winds thereon it will slip back (longitudinally) automatically to the center of the drum for automatic return, and without overwinding and locking.

The control and means for moving the cable include, in the present form of the invention, an electric motor 20, which is coaxially mounted with and is directly connected to the drum and rotates the same. The electric motor 20, in the present form of the invention, is of the reversible type. The direction of rotation may be manually reversed by throwing the manually operable reversing switch 21 from one motor energizing position to another. When the drum is to be stopped, the reversing switch may be opened. The drum supporting shaft 22 supports a brake drum 23 and hingedly supported as at 24 is a board 25 having the handle portion 26. When the rider of the sea-sled falls off in the travel of the sea-sled from one end of the pool to the other, the 75 load is relieved from the cable and the motor starts to race. To load the motor, the attendant or operator grasps the handle 26, elevates the board 25 upon its hinge 24 into contact with the drum 23, thereby again loading the motor. Opening the switch 21 will stop the motor and permit the sea-sled to be righted and again occupied.

If substantially continuous travel is desired, the motor may also be equipped with an automatic control of the automatic reversing type and herein, the same is indicated by the numeral 126. To prevent motor racing and accidents due thereto, a governor 27 may be associated with the shaft 22 and this governor through the lever 28 may operate the brake shoe 29 to engage a portion of the drum surface 23 for holding down the speed of the motor and the drum.

The motor, drum and all of the aforesaid 100

mechanism is preferably supported on a platform 30, which platform is provided with extended handles 31 and is also provided with the legs 32. The legs 32 are provided with 5 casters 33 which are of the so-called brake type, that is, the wheels may be clamped so that the platform will not roll. Any other suitable means may be provided for portability and rigid anchoring.

10 The invention claimed is:—

1. Cable handling mechanism for an amusement device for swimming pools comprising a motor, a cable winding drum reversibly winding the cable, and means automatically controlling the direction of rotation of the drum.

15 2. Cable handling mechanism for an amusement device for swimming pools comprising a motor, a cable winding drum reversibly winding the cable, and means arranged for automatically braking the drum when the cable load is relieved.

20 3. Cable handling mechanism for an amusement device for swimming pools comprising a motor, a cable winding drum reversibly winding the cable, means automatically controlling the direction of rotation of the drum, and means arranged for automatically braking the drum when the cable load is relieved.

25 4. The combination with a swimming pool, and a sea-sled, of an endless cable extending across the pool and to which the sea-sled is connected, of a pulley mounted at one side of the pool for supporting the cable, a drum at

30 the opposite side of the pool about which a portion of the cable is wound, reversible power means for reversibly rotating the drum to move the sea-sled to and fro across the pool, a support for the drum and power means, means on the support for manually moving the support, and means for rigidly positioning the support when in the desired location.

35 5. A device as defined by claim 4, characterized by the surface of the drum being so arranged that as the cable is wound thereon it automatically shifts longitudinally for freeing itself and preventing overwinding and locking.

40 In witness whereof I have hereunto affixed
50 my signature.
